UNITED STATES PATENT OFFICE.

JOHN B. PETERS, OF TOLEDO, OHIO, ASSIGNOR TO THE ELECTRIC AUTO-LITE COMPANY, OF TOLEDO, OHIO, A CORPORATION OF OHIO.

ENGINE-STARTER.

1,185,931.

Specification of Letters Patent.

Patented June 6, 1916.

Application filed December 4, 1913. Serial No. 804,726.

To all whom it may concern:

Be it known that I, JOHN B. PETERS, a citizen of the United States, and a resident of Toledo, in the county of Lucas and State of Ohio, have invented a certain new and useful Engine-Start; and I do hereby declare the following to be a full, clear, and exact description of the invention, such as will enable others skilled in the art to which it appertains to make and use the same; reference being had to the accompanying drawings, and to the characters of reference marked thereon, which form a part of this specification.

This invention relates particularly to starting means for internal combustion engines of automobiles, but is not restricted to such use as it may be used in any connection for which it may be adapted or appropriate.

The object of my invention is the provision of simple and efficient engine starting means of the character described whereby to enhance the practicability and commercial value thereof.

Further objects and advantages of the invention will be apparent from the following description.

The invention is fully described in the following specification, and while in its broader aspect, it is capable of embodiment in numerous forms, a preferred and two modified forms thereof are illustrated in the accompanying drawings, in which,—

Figure 1 is a plan view of an automobile engine and portions of an associated chassis with my invention associated therewith. Fig. 2 is a perspective view of one embodiment of my invention, with portions broken

away and in section, and with the parts thereof in normal position. Fig. 3 is a rear elevation of the starter gear and its carrying member, with the gear in driving engagement with the engine fly-wheel or driven

gear. Fig. 4 is an enlarged detail of portions of the drive and driven gears, illustrating the formation of the teeth thereof. Fig. 5 is a perspective view of a different embodiment of the invention, with portions

broken away and removed and with the parts in normal position. Fig. 6 is a rear elevation of the drive gear, its carrying parts and a portion of the driven gear with the drive gear in normal position. Fig. 7 is a side elevation of a manually controlled

form of the invention with parts broken away. Fig. 8 is a rear elevation of the drive gear, the carrying parts therefor and a portion of the driven gear of such form with the drive gear in normal position, and Figs. 60 9, 10 and 11 are wiring diagrams respectively for the forms of the invention shown in Figs. 2, 5, and 7.

Referring to the drawings, 1 designates the frame of an automobile chassis; 2 an internal combustion engine carried thereby; 3 the engine fly-wheel, which has its periphery provided with a circumferential series of gear teeth, and 4 the electric generator, which is suitably connected to the engine 70 shaft whereby current is generated during a running of the engine, as is well understood in the art. The generator 4 has leads 5 extending therefrom to a storage battery 6, which is customarily located on one of the 75 running boards of the automobile, but which may be disposed in any other suitable or convenient position. An underload circuit breaker 5^a is disposed in the generator leads 5, whereby the battery remains cut off from 80 the generator when less than a predetermined current is being generated thereby.

Referring particularly to Figs. 1, 2, 3 and 4 in which one embodiment of my improved 85 starter plant is shown, 7 designates an electric motor which is preferably mounted adjacent to the battery 6 so as to shorten the leads 8 between the battery and motor, whereby the current loss between such parts is reduced to a minimum and the efficiency 90 of the plant improved over the styles of plants in which the motor is located adjacent to the engine and a considerable distance from the battery.

A switch is disposed in the motor circuit, 95 being mounted, in the present instance, in a box 9 over the motor and having separate terminal parts 10 adapted to be connected by a sliding switch part 11. The switch part 11 is carried by a shift-rod 12 which movably extends through the box and is operated as hereinafter described. Any other suitable form of switch may be provided however, as desired.

The shaft 13 of the motor 7 extends forward therefrom and carries a small drive-gear 14 at its forward end in position to mesh with the teeth on the fly-wheel or large gear 3 on the engine shaft. The shaft 13 is carried adjacent to the drive-gear 14 by the 110

inner forked end of a rocker-lever 15, which is journaled in a bracket 16 projecting from an adjacent frame part and is adapted, when rocked, to move the gear 14 into and out of mesh with the gear 3. To facilitate such transverse movement of the gear 14 the shaft 13 is of a flexible nature, being provided with one or more universal joints 17. The 5 end of the lever 15, which is opposed to the shaft-carrying end thereof, projects outwardly from its fulcrum in the bracket part 16 transversely of the chassis frame and is connected by an upwardly projecting rod or link member 18 to the free end of a forwardly projecting lever arm 19, which is fulcrumed in a fixed bracket or frame part 20 and has a rearwardly projecting arm 19^a.

A solenoid 21 is fixedly carried by a part of the bracket 16 below the lever arm 19, and 20 has its movable plunger part 22 in connection with such lever arm, as shown. The coil of the solenoid is in closed circuit, through leads 23, with the generator leads 5, at the generator side of the circuit breaker 25 5^a whereby the solenoid will be energized upon a generating of current by the generator 4 when the battery is cut off, and the movable part 22 will be attracted to move downward to communicate a throwing out 30 movement to the lever 15 and drive gear 14 carried thereby.

The lever arm 19^a, which is attached to and has movement with the lever arm 19, has an apertured free end part 19^b through 35 which the forward end of a draft-rod 24 loosely projects for reciprocatory movements therein. This draft-rod has its rear end attached to the switch-rod 12 and adjustably carries a collar 25 adjacent to its forward 40 end. The collar 25, in the present instance, is yieldingly connected by a coiled contractile spring 26 to the bracket-arm 27 extending from a cross-frame bar 28, such spring normally tending to maintain the forward 45 end of the rod 24 lowered in position for the rear end of the collar 25 to be engaged by the upper end of a rocker-arm 29 when swung forward, whereby to communicate a 50 switch closing movement to the switch-rod 12. The rocker-arm 29 rises from a rock-shaft 30, which is journaled, in the present instance, in a part of the bracket-arm 27, and carries the foot-pedal 31, which may be either the clutch pedal or brake pedal 55 temporarily used in automobiles, or may constitute an entirely separate and independent pedal or operating part. A spring 22^a may also be mounted on the plunger 22 to act alone, or to assist the spring 26 in maintaining 60 the parts in normal position.

The lowering of the forward end of the draft-rod 24 by the action of the spring 26, in addition to moving the collar 25 into register with the upper end of the rocker-arm 65 29, also rocks the lever 19—19^a in a direc-

tion to move the drive-gear 14 into mesh with the gear 3, thus normally maintaining the gears 3 and 14 in mesh when the engine is at rest. The switch-rod 12 projects, in the present instance, without the rear end 70 of the switch-box 9 and carries a coiled compression spring 32, which urges the switch-rod 12 and draft-rod 24 rearward to switch opening position. It is evident that while I have provided a foot-pedal 31 and connected 75 rocker-arm 29 to be manually operated to communicate switch closing movements to the switch 10—11, any other suitable mechanism may be provided for such purpose as desired without departing from the spirit of 80 the invention.

To facilitate the operation of my improved starter mechanism the teeth of the gears 3 and 14 are peculiarly formed, whereby the gear 14, when driven by the motor, is 85 adapted to impart an engine starting movement to the gear 3, and such latter gear is adapted to throw or force the gear 14 outward from mesh therewith when the inertia or speed of driving of the gear 3 by the engine becomes greater than the driving action of the gear 14 thereon. For this reason the faces *a*, *a* (see Fig. 4) of the teeth of the respective gears 3 and 14, which have driving coaction when the gear 14 is acting as the 90 driver, are of standard tooth form, while the opposite faces of such teeth are inclined to such an extent, as indicated at *b*, *b* in Fig. 4, to cause the teeth of the gear 3 when acting as the drive-gear to have a cam-like or outward forcing action on the teeth of the gear 14. It is thus apparent that the coaction of the teeth of the gears 3 and 14 when the gear 3 is acting as the driver is such as to alone throw the gear 14 out of mesh with the 95 gear 3, or to assist the solenoid 21, when energized, in throwing the gear 14 to inoperative position. It will be understood that when the gear 14 is thrown out of mesh with the gear 3, the solenoid 21, which is then energized, acts to retain the gear 14 in inoperative position during the continued running of the engine, or so long as the generator 4 is generating a sufficient current to 100 energize the solenoid for such purpose.

A diagram of one form of wiring for the above form of my invention is illustrated in Fig. 9 and will be readily understood. The operation of this form of my invention is as follows: When the engine is at rest the 105 switch 10—11 stands open and the spring 26 causes the collar 25 to stand in position to be engaged and moved by the rocker-arm 29 upon a depression of the foot pedal 31, and also causes the draft-rod 24 to hold the 110 lever 19—19^a rocked in position to maintain the drive-gear 14 in mesh with the gear 3. The circuit breaker 5^a also stands open. To start the engine the operator depresses the 115 foot-pedal 31 to move the draft-rod 24 for- 120

ward and effect a consequent closing of the motor circuit 8 with the battery 6, whereupon the motor 7 is driven to impart driving rotation to the gear 14 and a consequent 5 turning of the gear 3 and crank-shaft of the engine. When the engine is started and the gear 3 is driven at a greater speed than the driving speed of the gear 14, the faces *b*, *b* of the gears 3 and 14 coact to cause an 10 outward forcing of the gear 14 from engagement with the gear 3, thus automatically disengaging the starting mechanism from the gear 3. When the gear 3 is driven at a sufficient speed to cause such automatic disengaging of the starting mechanism therewith, the engine will be driving the generator 4 at a speed necessary for generating a sufficient current in the solenoid line to energize the solenoid and maintain the gear 14 in 15 an inoperative position. The movement which is imparted to the lever 19—19^a by the solenoid will also raise the forward end of the draft-rod 24 a sufficient height to release the engagement of the collar 25 with the rocker-arm 29, should the foot-pedal 31 be still depressed, thus permitting a retraction of the draft-rod 24 and switch-rod 12 by the action of the spring 32 to switch opening position. Upon a stopping of the engine the current 20 generating action of the generator 4 will cease thus permitting a demagnetizing of the solenoid and a consequent movement of the starter mechanism parts into position for the gear 14 to mesh with the gear 3, and for 25 the collar 25 to stand in position to be engaged by the rocker-arm 29 upon a rocking thereof so that the engine may be again started by the operator simply depressing the foot pedal 31.

30 In Fig. 5 is illustrated a slightly modified form of my invention, the modification consisting in so arranging certain parts of the starter mechanism that the solenoid thereof will serve to retain the parts in engine generating action of the generator 4 will cease thus permitting a demagnetizing of the solenoid and a consequent movement of the starter mechanism parts into position for the gear 14 to mesh with the gear 3, and for 35 the collar 25 to stand in position to be engaged by the rocker-arm 29 upon a rocking thereof so that the engine may be again started by the operator simply depressing the foot pedal 31.

40 In Fig. 5 is illustrated a slightly modified form of my invention, the modification consisting in so arranging certain parts of the starter mechanism that the solenoid thereof will serve to retain the parts in engine 45 starting position instead of out of such position, as was the case with the construction of starter above described. In this form of the invention 40 designates a foot or control-pedal having a rocker-arm 41 for engagement with a collar 42 on the draft-rod 43 which has connection with the movable part of a switch 44 in circuit with the starting motor 45. The draft-rod 43 has loose sliding connection with one arm of a lever 55 46, the other arm of which is connected to the plunger or movable part 47 of a solenoid 48. The solenoid 48 is disposed in circuit with the battery 6 of the machine through leads 49, having a normally open switch 50 disposed therein, which switch is closed by the depression of a push button 51, or in any other suitable manner, as shown by the wiring diagram in Fig. 10. A coiled compression spring 52 is mounted on the outer 55 end portion of the plunger 47 intermediate

the solenoid case and the outer end of the plunger, and serves to urge the plunger 47 and lever 46 into position to hold the collar 42 out of the path of movement of the rocker-arm 41, and also to retain the starter 70 gear 53 out of mesh with the gear 3 of the engine, the gear 53 being connected to the lever 46 through the medium of the rocker-lever 54 and link 55 in the same manner as described in connection with the form shown 75 in Fig. 2. Upon a closing of the switch 50 the battery circuit with the solenoid is closed and the plunger 47 attracted upward, thereby moving the collar 42 into position to be engaged by the rocker-arm 41 and 80 moving the starter gear 53 into mesh with the engine gear 3. This being done the operator depresses the pedal 40 to close the motor circuit whereby a driving action is communicated to the gear 53 through the 85 motor shaft 56. When the engine has been properly started, the operator either effects or permits an opening of the switch 50 in the solenoid circuit so that the plunger 47 is no longer attracted by the solenoid and is 90 permitted to move downward under the action of the spring 52, thus moving the collar 42 out of rocker-arm engaging position and the gear 53 out of mesh with the gear 3. The formation of the teeth of 95 the gears 3 and 53 in this form of the invention are the same as shown in Fig. 4 to permit the gear 53 to have a driving action on the gear 3 when the latter is being driven by the starting motor, and to cause the gear 100 53 to be thrown outward from engagement with the gear 3 when the latter has attained a speed greater than the speed of driving of the gear 53 by the motor.

105 In the form illustrated in Fig. 7 the parts of the starter mechanism, their arrangement and action are the same as with the form shown in Fig. 5, except that a foot, or manually controlled pressure-rod is substituted for the solenoid of said latter form. 110 In this form 60 designates the starting motor; 61 the motor-shaft carrying the starting gear 62; 63 the rocker lever carrying the starting gear; 64 the rod connecting the lever 63 to the lever 65; 66 the motor switch; 67 the draft-rod for the switch, having its forward end working through the rear end portion of the lever 65 and carrying the collar or shouldered part 68, and 69 the foot 115 pedal to which the rocker-arm 70, for engaging the collar 68 is connected. The control means for the lever 65 comprises, in the present instance, a pressure rod 71, which attaches at its lower end to the rear end portion of the outside lever and extends upward therefrom through a superimposed guide part 72, which may comprise the floor portion of an automobile and has its upper end normally held elevated a predetermined 120 distance above the part 72 by the action 130

thereon of a coiled compression spring 73. This spring is disposed between the guide part 72 and the upper headed end of the pressure rod, and is of sufficient strength 5 to normally maintain the gear 62 and collar 68 in inoperative position. Upon a depression of the rod 71 the lever 65 is rocked to lower the collar 68 into rocker-arm engaging position and to move the parts 63 and 64 to 10 throw the gear 62 into mesh with the gear 3. Upon a release of the pressure rod 71 the parts controlled thereby assume their normal positions. It is evident that any other suitable form of manually operable means 15 for controlling the movements of the lever 65 may be provided without departing from the spirit of the invention, the present means being shown on account of its simplicity. A wiring diagram for this form 20 of the invention is shown in Fig. 11, it being necessary to merely connect the generator 4 and motor 7 with the battery.

It is evident that I have provided a simple and efficient starter mechanism for internal combustion engines which is capable 25 of being operated or of having its movements controlled in various ways, and which has one gear radially movable into and out of mesh with another gear instead of axially 30 sliding into and out of engagement therewith as is customary with a large number of starter mechanisms of this type. While this feature is considered important the invention is not restricted to such action as 35 the gears might be engaged in other manners if desired.

It is to be understood that the forms shown are merely illustrative of the invention and that numerous changes may be 40 made therein without departing from the spirit of the invention.

Having thus described my invention, what I claim as new, and desire to secure by Letters Patent, is,—

45 1. In combination, a driven member, a drive member movable into and out of engagement with the driven member transversely of its axis, means for rotating said drive member, means for controlling the action of said member rotating means, and means embodying an electro-magnetic feature operable to control the movements of 50 said drive member into and out of engagement with the driven member.

55 2. In combination, a driven member, a drive member movable into and out of engagement with the driven member transversely of its axis, a manually controlled motor for imparting rotation to said drive member, and mechanism operable to control the transverse movements of said drive member and embodying both mechanical 60 and electrical features.

3. In an engine starter, a driven member, 65 a drive member movable into and out of en-

gagement with said driven member transversely of its axis, a manually controlled motor for imparting rotation to said drive member, and mechanism normally maintaining said drive member in one position of 70 its transverse movement and electrically operable to move the drive member from its normal position.

4. In an engine starter, a driven member, a drive member movable into and out of engagement with the driven member transversely of its axis, a flexible shaft for said drive member, an electric motor for driving said shaft, mechanism for controlling the transverse movements of said drive member, 80 said drive and driven members having interengaging parts which automatically act to break the driving connection between said members when the driven member has attained a predetermined speed. 85

5. In an engine starter, a driven member, a drive member movable into and out of engagement with the driven member transversely of its axis, an electric motor, a flexible shaft connecting said motor and 90 drive member, and mechanism operable to control the transverse movements of said drive member and the action of said motor.

6. In an engine starter, a motor, a driven member, a drive member actuated by said motor and movable into and out of engagement with the driven member transversely of its axis, and relatively to the motor, means for imparting rotation to the drive member, and mechanism for controlling the 100 transverse movements of the drive member and having a rocker part carrying such member. 95

7. In an engine starter, a driven member, a drive member movable into and out of engagement with the driven member transversely thereof, a manually controlled motor, flexible shaft connection between the said motor and drive member, and mechanism operable to control the transverse movements of said drive member and the action of said motor, and having a 110 rocker part carrying said member. 105

8. In an engine starter, a driven member, a drive member movable into and out of engagement with the driven member, means for driving said drive member, mechanism operable to impart transverse movements to said drive member, and control means, in part electrical, in connection with said 115 mechanism normally operable to maintain the mechanism in one position of its member actuating movements. 120

9. In an engine starter, a driven member, a drive member movable into and out of engagement with the driven member transversely of its axis, motor means having a flexible shaft carrying said drive member, mechanism operable to impart transverse 125 movements to the drive member, and control 130

means, in part electrical, in connection with said mechanism normally operable to maintain the mechanism in one position of its member actuating movements.

10. In an engine starter, a driven member, a drive member movable into and out of engagement with the driven member, mechanism operable to impart shifting movements to the drive member, control means for said mechanism normally maintaining the mechanism in one position of its movement and operable to impart reverse movement thereto, an electric motor for said drive member, a switch in circuit therewith, and means operable to close said switch when said mechanism is in a predetermined position of its movement.

11. In an engine starter, a driven member, a drive member movable into and out of engagement with the driven member, an electric motor in driving connection with said drive member, a switch in circuit with said motor, and mechanism operable to control the shifting movements of said drive member and the opening and closing movements of said switch and having a control part which is manually operable to actuate a part of the mechanism to close the switch when the drive member shifting part of the mechanism is in a predetermined position of its movement.

12. In an engine starter, a driven member, a drive member movable into and out of engagement therewith, an electric motor for said drive member, a normally open switch in circuit with said motor, and mechanism operable to control the shifting movements of said drive member and the closing movements of said switch and having means for controlling the movements of the member shifting part of the mechanism, and a control part which is manually operable to effect a closing of the switch when the gear shifting part of the mechanism is in a predetermined position of its movement.

13. In an engine starter, a driven member, a drive member movable into and out of engagement therewith, a motor for said drive member, mechanism operable to shift said drive member relatively to the motor, and control means for said motor in connection with said mechanism and manually operable to render the motor active when said mechanism is in a predetermined position of its member shifting movement.

14. In an engine starter, a driven member, a drive member movable into and out of engagement with the driven member, mechanism operable to shift said drive member, a motor for said drive member, and control mechanism for said motor having a part in connection with said mechanism movable therewith in one direction and relative thereto in another direction, said control means also having a manually operable element for

engaging and moving said part in one direction to render the motor active when said mechanism is in a predetermined point of its drive member shifting movement.

15. In an engine starter, a driven member, 70 a drive member shiftable into and out of engagement therewith, mechanism operable to shift said drive member, a motor for said drive member, control means for the motor having an oscillatory and longitudinally 75 movable part in connection with said mechanism and having oscillatory movements imparted thereto by movements of the mechanism, and manually movable means operable to engage and impart longitudinal movements to said part whereby to operate said control means to render the motor active when said part is in a predetermined position of its oscillatory movement.

16. In an engine starter, a driven member, 85 a drive member shiftable into and out of engagement with the driven member transversely of its axis, mechanism operable to shift said drive member, a motor for said drive member, control means for the motor 90 having an oscillatory and longitudinally movable part in connection with said mechanism and having oscillatory movements imparted thereto by movements of the mechanism, and manually movable means operable to engage and impart longitudinal movements to said part whereby to operate said control means to render the motor active when said part is in a predetermined 95 position of its oscillatory movements.

17. In an engine starter, a driven member, 100 a drive member, a lever carrying the drive member for movements into and out of engagement with the driven member, a second lever, connection between said levers 105 to impart rocking movements from one to the other thereof, means controlling the movements of said levers, a motor for said drive member, and manually controlled means operable to render the motor active.

18. In an engine starter, a driven member, a drive member, a rocker lever carrying said drive member for movements into and out of engagement with the drive member, a second rocker lever, connection between said levers for imparting rocking movements from one to the other thereof, a motor for said drive member, and control means for the motor having a part in connection with and movable by one of said levers, and a part 115 manually movable to engage and move said first part when in one position of its lever actuated movement whereby to operate said means to render the motor active.

19. The combination with an engine and a rotatable part thereof, of a drive member shiftable into and out of engagement with said part, an electric motor disposed at the rear of the engine and in driving connection with said member, a storage battery adj-

cent to said motor and in circuit therewith, a normally open switch in circuit with said motor and battery, means for imparting shifting movements to said drive member, and means operable to close said switch.

20. The combination with an engine and a rotatable part thereof, of a drive member for said part, means operable to impart rocking movements to said member to place it into and out of engagement with said part, an electric motor disposed at the rear of the engine, a flexible shaft connecting said motor and part, and means for controlling the operation of said motor.

15 21. In an engine starter, a driven member, a drive member movable into and out of

engagement with the driven member, mechanism operable to impart shifting movements to the drive member, control means for said mechanism normally maintaining 20 the mechanism in one position of its movement and operable to impart reverse movements thereto, and a motor for said drive member.

In testimony whereof, I have hereunto 25 signed my name to this specification in the presence of two subscribing witnesses.

JOHN B. PETERS.
